UNITED STATES PATENT OFFICE

VITTORIO OREGGIA, OF SAN REMO, ITALY

CLOSURE FOR BOXES AND CASES

Application filed April 14, 1928, Serial No. 270,002, and in Italy April 15, 1927.

This invention has for its object a safety closure for cases and boxes, that can be used also in connection with trunks, portmanteaus, etc. and is very strong and safe, rapidly 5 opened and closed without nailing the lid and has the great advantage that the packing material can be re-utilized indefinitely by simply changing each time the single safety seal. This is obtained essentially by 10 a cross binding connected to a seal, of the type prescribed by railway companies, post-offices etc. The binding can be replaced by a band of thin sheet iron, or both appliances, binding and strips can be combined together 15 in various manners. The bindings or strips provided in a larger or smaller number according to the size of the box end to a single seal, and by destroying this latter the box is opened without having to remove nails 20 or undo knots, while it is possible to re-utilize the whole material as a new packing without disassembling and thereafter assembling the parts together again.

The corners of the boxes or cases can be 25 provided with reinforcing members made of curved sheet metal, and held in place by the same bindings with which they can be reutilized. The strings or cables used for binding can be attached to the box walls in a permanent manner by staples or temporarily by 30 means of pins, which are removed when opening the box and re-utilized thereafter with the other parts.

The accompanying drawing shows by way 35 of example some constructional forms of this invention.

Figures 1 and 2 are perspective views showing in the open and closed position, respectively, a box of which the closure is made 40 strong and safe by cross bindings with sheet metal reinforcing members.

Figure 3 is a detailed view of the safety closure shown in Figures 1 and 2.

Figure 4 shows a box in which the closure 45 is insured by cross bands of sheet metal and by a binding in the direction of the length of the box.

Referring to Figures 1 and 2, the box 1 and its lid 2, simply superposed to the box, 50 is closed by a binding comprising two par-

allel cross strips and a longitudinal strip, each of which is formed by a double string. The terminals 17 and 18 of the cross strips end at the longitudinal axis of the lid, and the opposite terminals 19 and 20, projecting from the side wall of the box, are longer and serve for completing the longitudinal strip, as hereinafter explained. The longitudinal strip ends by its terminal 16 at the adjacent cross binding and by its opposite terminal 15 at the upper edge of the wall side. The closure is effected as follows: the lid 2 is placed on the box 1, the terminals 16 and 17 are placed on the lid and superposed to the eyelets formed by the double strings.

The terminal 19 is passed through said eyelets and then bent at right angles and brought into a longitudinal direction, the terminal 18 is placed on the lid and its eyelet is brought upon the eyelet of the terminal 19; the terminal 20 is passed through said eyelets, bent at right angles and connected to the end 15 of the longitudinal strip by means of a loop provided with a seal as shown in Fig. 3.

The closure is stiffened and reinforced by angle irons 13, made of curved sheet metal, hinged to the four walls of the box in correspondence of each bending of the strings 15, 16, 17, 18, 19 and 20. The angle irons can be fixed to the lid instead of to the box. The box is further strengthened by two end bands of sheet metal, of which the bridge pieces 34 are tilttable.

In Figure 4 the double strings of the strips shown in Fig. 1 are replaced by bands of sheet metal. The ends of bands 37 and 38 respectively of both bindings are provided with holes which, when the ends are swung down on the lid, are superposed on the middle of this latter; loops 39 and 40 being passed through said holes. The longitudinal band is completed by these loops, the loop 39 passes through the ends of bands 36 and 37, and the loop 40 through the loop 39 and the ends of bands 38; a loop with a seal is passed through the loop 40 and the end 35 of band 36 and makes the box reliably strong and safe. The bridge pieces 34 can

be reinforced by means of a steel cable 33 or sheet metal 33' secured to the box wall; moreover one of the bridge pieces can be traversed by the same sealed loop connecting the end 35 to the loop 40.

5 My invention can be embodied by a number of other constructions by combining bands and strings in various manners.

What I claim is:

- 10 1. A tying band for packing boxes comprising an incomplete band in the direction of the length of the box, a plurality of cross bands, formed by double strings with interlocked eye-shaped ends adapted to complete the longitudinal band, a loop for connecting the free ends of said bands, and a seal for said loop. 75
- 15 2. A tying band for packing boxes comprising an incomplete band in the direction of the length of the box, a plurality of cross bands longer than the periphery of the cross section of the box, said bands consisting of double strings so arranged that the longer section of one of the outer cross bands 25 passes through the eyelets formed at the end of the other section of said band and at an end of the incomplete longitudinal band, then extends lengthwise over the lid and ends at the adjacent cross binding, the longer section of which passes through the eyelets of said extension and of the other end of this latter cross band, and so on, a loop for connecting the free ends of said bands, and a seal for said loop. 80
- 20 3. A tying band for packing boxes comprising an incomplete band in the direction of the length of the box, a plurality of cross bands, said bands consisting of double strings and the cross bands being interlocked 25 with one another and with the incomplete longitudinal band so as to complete this latter, means for securing said bands to the box body in a permanent manner, a loop for connecting the free ends of said bands interlocked with one another and a seal for said loop. 95
- 25 4. A tying band for packing boxes comprising an incomplete longitudinal band, a plurality of cross bands, said bands consisting of double strings interlocked with one another so as to complete the longitudinal band, a loop for connecting the free ends of said bands interlocked with one another, a seal for said loop, and a reinforcing bridge 50 piece of sheet metal pivoted to each side of the box, and capable of being swung down and fastened upon the lateral lid ends. 100
- 30 5. A tying band for packing boxes comprising an incomplete band in the direction of the length of the box, the ends of said band being eyelet-shaped, a plurality of cross bands with eyelet-shaped ends, means for hooking together the adjacent ends of 55 said bands and completing the longitudina 105

band, a loop for connecting the free ends of said band, and a seal for said loop.

In testimony that I claim the foregoing as my invention, I have signed my name.

VITTORIO OREGGIA. 70
